UNITED STATES PATENT OFFICE.

CLARA HANSON, OF WITTENBERG, WISCONSIN.

MATTRESS ATTACHMENT.

1,372,505.

Specification of Letters Patent. Patented Mar. 22, 1921.

Application filed June 11, 1920. Serial No. 383,288.

To all whom it may concern:

Be it known that I, CLARA HANSON, a citizen of Wisconsin and U. S. A., residing at Wittenberg, in the county of Shawano and State of Wisconsin, have invented new and useful Improvements in Mattress Attachments, of which the following is a specification.

This invention comprehends the provision of a mattress attachment designed to prevent wetting of the mattress by patients who are confined to their bed.

Most specifically stated, the invention embodies a sheet of water-proof material which is detachably secured to the mattress, and having an opening therein which communicates with a tube depending from the said sheet through the mattress, to convey the urine into a suitable receptacle arranged beneath the bed.

The nature and advantages of the invention will be better understood when the following detailed description is taken in connection with the accompanying drawings, the invention residing in the construction, combination and arrangement of parts as claimed.

In the drawings forming part of this application, like numerals of reference indicate similar parts in the several views, and wherein:

Figure 1 is a top plan view of a mattress showing the invention associated therewith.

Fig. 2 is a transverse sectional view taken on line 2—2 of Fig. 1.

Fig. 3 is a longitudinal sectional view through the bed showing the attachment in position for use.

Fig. 4 is a fragmentary detail view showing the receptacle separated from the tube.

Referring to the drawings in detail, A indicates a mattress of any suitable and well-known construction supported upon the springs B of the bed, the attachment forming the subject matter of the invention being indicated generally at C.

This attachment comprises a sheet of water-proof material, preferably of rubber, although any other suitable material may be employed. The sheet is indicated at 10 and may vary in dimension without departing from the spirit of the invention. The cen-

tral portion 11 of the sheet is relatively thick and has associated therewith a tube 11^a which extends from the sheet 10 through the mattress A and the springs B, the tube opening at the surface of the sheet 10. The sheet may be detachably secured to the mattress A in any suitable manner, preferably by snap fasteners indicated at 12. The tube 11 may terminate immediately beneath the bed, in which instance it has detachably associated therewith a rubber receptacle 14, or the tube may extend close to the floor and terminate immediately above any suitable receptacle, not shown, which may be supported upon the floor immediately beneath the tube. The attachment in place prevents the mattress from being soiled by patients who are confined to their bed, urine being conveyed through the tube into the receptacle 14, or to the other receptacle above mentioned. A relatively thick portion of the sheet 10 is further provided with tucks or ribs 15 which are convergently disposed, the adjacent ends of the respective tucks or ribs terminating at opposite sides of the adjacent end of the tube 11. These tucks or ribs serve to guide the urine into the tube 11.

While it is believed that from the foregoing description the nature and advantages of the invention will be readily apparent, I desire to have it understood that I do not limit myself to the details herein shown and described, and that such changes may be resorted to when desired as fall within the scope of what is claimed.

What I claim is:

A mattress attachment comprising a sheet of water-proof material, a centrally raised portion formed on one side of the sheet and having a central opening, ribs arranged on the upper surface of the raised portion and convergently disposed from two adjacent corners and terminating in close proximity to said opening, means for detachably securing the sheet to the mattress, a tube depending from said opening through the mattress, and a receptacle carried by the lower end of the tube for the purpose specified.

In testimony whereof I affix my signature.

CLARA HANSON.
